UNITED STATES PATENT OFFICE.

CHRISTOPHER J. GRELLNER, OF ST. LOUIS, MISSOURI.

HAMMER.

SPECIFICATION forming part of Letters Patent No. 341,474, dated May 11, 1886.

Application filed December 21, 1885. Serial No. 186,324. (No model.)

To all whom it may concern:

Be it known that I, CHRISTOPHER J. GRELLNER, of the city of St. Louis, in the State of Missouri, have invented a certain new and useful Improvement in Hammers, &c., of which the following is a full, clear, and exact description, reference being had to the accompanying drawings, forming part of this specification, and in which—

10 Figure 1 is a side view, part in section, of a hammer embodying my invention. Fig. 2 is an end view of the wedge. Fig. 3 is a perspective view of the wedge, and Fig. 4 is a similar view in a modified form.

15 This invention relates to an improvement on the device shown and described in Letters Patent No. 261,338, granted to myself July 18, 1882.

20 With my improved form of device the wedge is made in one piece, and has an opening to receive the retaining member or nail.

Referring to the drawings, A represents the hammer, and B the handle.

25 C represents the wedge, which is made with a perforation, D. At this perforation the wedge is preferably enlarged by ribs F, as shown, which taper downward to the taper G of the wedge. The perforation is turned outward to one side of the wedge, and when the nail or 30 securing member is driven down its end comes against the incline formed by turning the perforations outward to one side of the wedge. With this form of wedge and manner of securing it in place there is no friction between the 35 retaining member and wedge as the former is driven in, and the wedge is securely and effectually held from coming out. The wedge is also in one part, which makes it cheaper,

and there is no danger of losing one of the parts, as where the wedge is made in two parts. 40

In the modification shown in Fig. 4 the openings for the retaining member are made in the ends of the wedge instead of the center, as shown in the other figures. In this modification are also shown ears C', which are intended 45 to engage the top of the hammer-head each side of the eye and to aid in holding the head upon the handle.

I claim as my invention—

1. The combination of the hammer, handle, 50 perforated wedge made in one piece, and retaining nail or member adapted to enter the perforation in the wedge and to be turned outward at its lower end through the perforations into the wood of the handle, as shown and described.

2. The combination of the hammer, handle, wedge having a perforation, ribs strengthening 60 the perforated portions of said wedge, and the nail or retaining member adapted to enter the perforation in the wedge and to be turned outward at its lower end into the wood of the handle, as described.

3. The combination of the hammer, handle, 65 perforated wedge, tapering ribs strengthening the perforated portions of said wedge, and retaining nail or member, the perforation turning outward through side of the wedge to form an incline, that acts to turn up the lower end of the nail or retaining member into the wood 70 of the handle, as described.

CHRISTOPHER J. GRELLNER.

In presence of—

SAML. KNIGHT,
BENJN. A. KNIGHT.
